UNITED STATES PATENT OFFICE.

ALFRED NELSON, OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

DAMPER FOR STOVE AND FURNACE FLUES.

1,165,115.

Specification of Letters Patent.

Patented Dec. 21, 1915.

Application filed August 12, 1914. Serial No. 856,427.

To all whom it may concern:

Be it known that I, ALFRED NELSON, a citizen of the United States, residing in Philadelphia, Pennsylvania, have invented 5 certain Improvements in Dampers for Stove and Furnace Flues, of which the following is a specification.

One object of my invention is to improve the construction of dampers for regulating 10 the draft of stoves and furnaces.

Another object of the invention is to make a damper which can be held in either the full open position or the closed position or in any intermediate position.

15 A still further object of the invention is to simplify the construction of the damper so that it can be economically manufactured.

In the accompanying drawings: Figure 1 is a front view of the damper in the closed 20 position, showing it applied to the pipe of a stove; Fig. 2 is a sectional plan view on the line *a—a*, Fig. 1; Fig. 3 is an enlarged rear view of the damper removed from the pipe; Fig. 4 is a sectional plan view on the line 25 *b—b*, Fig. 3; Fig. 5 is a sectional view on the line *c—c*, Fig. 3, showing the damper closed; Fig. 6 is a view on the same line, showing the damper in the full open position; and Fig. 7 is a sectional view on the line *d—d*, 30 Fig. 6.

Referring to the drawings, 1 is the stove pipe, in the present instance.

2 is the frame of the damper secured to the stove pipe, which is cut out so as to provide a clear opening for the hinged section 35 3 of the damper. The frame is secured to the pipe by screws or rivets 4. The hinged portion of the damper has pintles 5 and 6, which project through holes in the frame, as 40 shown in Figs. 1 and 2. The pintle 5 is cast integral with the frame while the pintle 6 is mounted on a plate 7 secured to the hinged portion 3 by a bolt 8 so that by removing the bolt the hinged portion of the damper 45 can be detached from the frame.

9 is a handle having a trunnion 10 mounted in the bearing 11 of the frame 2. The end of the trunnion is squared, as at 12, and mounted on the squared portion of this 50 trunnion is an arm 13, shaped as shown in Figs. 3 and 4. On the rear of the pivoted portion of the damper, and cast integral therewith in the present instance, is a cam-shaped projection 14. This projection 14 is 55 in the path of the arm 13 so that when the

handle 9 is moved from one side of the damper to the other it will bear upon the projection and will move the pivoted section from the open to the closed position. In the face of the pivoted section is a recess 15 and on the handle 9 is a projection 16. This recess has beveled walls, as shown in Figs. 1, 4, and 7, so that when the handle is in the position illustrated in Fig. 1 the damper is closed and the projection 16 rests in the recess 15 of the pivoted section, but when the handle is moved in the direction of the arrow, Fig. 1, then the projection 16 bears against one of the beveled sides of the recess and forces the pivoted section back to 60 the open position, the amount of opening being controlled by the arm 13.

In order to retain the handle 9 in any position to which it is adjusted, I form a series of shallow notches 17 in the upper 75 edge of the frame 2, and I form a rib 18 on the handle, which is arranged to enter any one of the notches and to retain the handle in any position to which it is adjusted, the spring of the metal of the handle 80 allowing it to pass the ribs forming the notches. The notches radiate from the center of the handle, as illustrated in Fig. 1. On one end of the rib 18 is a projection 19 and at each end is a step 20 with which 85 the projection 19 engages, as illustrated in Fig. 1, so as to limit the movement of the handle.

By the above construction, it will be seen that I am enabled to make the damper very 90 cheaply as the parts can be made without machining and can be easily assembled. The damper can be secured in any position to which it is adjusted.

I claim:

1. The combination in a damper, of a frame having an opening therein; a pivoted section having trunnions mounted in the lower portion of the frame and arranged to close the opening; a handle having a trunnion mounted in the bearing on the lower portion of the frame; an arm on the trunnion extending at the back of the pivoted section of the damper; a cam-shaped projection at the back of the damper in the path of the arm, the front of the pivoted section of the damper being recessed, said handle having a projection adapted to the recess so that when the handle is in one position and the damper is closed the projection 110

is in the recess and when the handle is moved the projection forces the pivoted section back toward the arm which controls the further movement of the pivoted section 5 of the damper.

2. The combination in a damper, of a frame; a pivoted section; a handle having a trunnion pivotally mounted in the lower portion of the frame; an arm on the trunnion extending back of the pivoted portion 10 of the damper, the frame having a series of notches at its upper edge, the handle having a rib arranged to enter any one of the notches as the handle is moved from one 15 position to another, the handle having a projection at one end of the rib; and stops at each side of the frame in the path of the projection so that the movement of the arm in either direction is limited.

3. The combination in a damper, of a frame having an opening therein; a pivoted section arranged to close the opening, said section having trunnions at its lower edge mounted in openings in the frame; a handle;

a trunnion mounted at the center of the 25 lower portion of the frame, the handle being arranged to swing from one side of the frame to the other, the trunnion having a squared portion at its inner end; a shaped-arm mounted on the squared portion; a cam-shaped projection at the rear of the pivoted portion and cast integral therewith and arranged in the path of the arm, the face of the pivoted portion having a recess; a projection on the handle arranged to enter the 30 recess when the damper is closed; a series of recesses in the upper portion of the frame; and a rib on the handle arranged to enter the recesses so as to hold the arm in the position to which it is adjusted.

In testimony whereof, I have signed my name to this specification, in the presence of two subscribing witnesses.

ALFRED NELSON.
